JOHN E. BELL, OF BROOKLYN, NEW YORK, ASSIGNOR TO SINCLAIR REFINING COMPANY, OF CHICAGO, ILLINOIS, A CORPORATION OF MAINE.

OPERATION OF PRESSURE STILLS.

Application filed July 26, 1924. Serial No. 728,307.

This invention relates to improvements in the cracking of hydrocarbon oils and distillates of high boiling point, such as gas oils and the like, to form more volatile or lighter hydrocarbon oils such as those which constitute commercial gasoline or pressure distillate.

The invention includes improvements both in the construction and operation of pressure stills, and in methods and apparatus for pressure distillation.

The invention relates more particularly to pressure stills provided with reflux towers, and methods of pressure distillation or cracking in which the vapors from the pressure still are subjected to a refluxing operation; and the invention includes improvements in the construction and operation of such pressure stills and reflux towers and in the refluxing operation. In particular, the invention includes improvements in the fractionation or fractional condensation of the vapors from pressure stills, and the preheating of the feed thereby, whereby the operation of the pressure still may be improved, and important heat economies effected.

In cracking hydrocarbon oils for the production of gasoline by distillation under pressure in pressure stills provided with reflux towers, the crude pressure distillate discharged from the top of the reflux tower may contain, in addition to the lighter hydrocarbons suitable as components of commercial gasoline, hydrocarbon of a kerosene character or others even heavier. It has heretofore been customary to subject all of the vapors escaping from the reflux tower to condensation in a water condenser to give a so-called pressure distillate, and then to re-distill the condensate or pressure distillate so obtained in order to fractionate it and separate a merchantable gasoline therefrom.

This method of condensation of pressure distillate involves a large and important loss of heat, inasmuch as the heat of the vapors condensed is dissipated in the cooling water in the condenser, and additional heat is then required for the redistillation. In addition to this redistillation, and the heat required therefor, additional expense is required in handling the pressure distillates.

One of the objects of the present invention

is to dispense with this redistillation, either partially or entirely, and to recover and utilize in the pressure distillation the heat, or 55 a considerable part of the heat, which the vapors contain, and which is now dissipated and lost.

According to the present invention, the vapors escaping from the reflux tower of the pressure still are caused to pass in indirect heat interchanging relation with fresh feed or charging stock for the still, and such fresh feed or charging stock is thereby preheated, while the vapors are themselves subjected to 65 condensation, thus eliminating the use of a water condenser for their condensation. This indirect heat interchange of the vapors from the still with the fresh feed is advantageously carried out in a countercurrent 70 fractionating tower in which the vapors as they come from the reflux tower are subjected to fractionation or fractional condensation and are separated into a series of fractions, and the fresh charging stock or feed is progressively heated to higher temperatures by 75 indirect contact with vapors undergoing condensation at progressively higher temperatures.

The invention also provides an improved 80 means and method for controlling the operation of reflux towers on pressure stills, and improvements in the general method of pressure distillation when carried out with such reflux towers. The invention enables a 85 marked heat economy to be obtained in the pressure still, and in its operation, and provides a combined operation of improved efficiency.

According to the present invention, the vapors from the pressure still are first subjected to a refluxing operation, which may advantageously be a refluxing operation in which the vapors are directly contacted with fresh charging stock or oil introduced into 95 the reflux tower and into direct contact with the vapors therein. After this refluxing operation, the remaining vapors from the reflux tower, which may contain vapors resulting from vaporization of part of the feed or 100 charging stock (in case special oil or charging stock is introduced into the reflux tower), are subjected to indirect heat interchanging relation with fresh charging stock passing

to the pressure still, thus preheating the charging stock and cooling and condensing the vapors. This heat interchange is advantageously carried out in a fractionating 5 tower or other apparatus providing for countercurrent flow of the vapors and charging stock, so as to obtain a regulated fractionating or condensing operation for fractionating the vapors into a series of fractions or 10 cuts, and progressively heating the fresh oil or charging stock to progressively higher temperatures.

Where fresh charging stock is thus employed for cooling and condensing the vapors 15 and for effecting fractional condensation of them, the resulting preheated charging stock may be directly introduced into the pressure still, or it may be introduced, in part or in whole, into the reflux tower and into direct 20 contact with the vapors undergoing refluxing therein. Where the preheated charging stock is introduced directly into the pressure still, other fresh charging stock, of the same or different character, may be introduced into 25 the reflux tower and into direct contact with the vapors therein to effect the desired refluxing operation.

In my prior application filed March 24, 1924, Serial No. 701,397, there is described an 30 improved method of fractionating the vapors from the reflux tower on a pressure still by passing them successively through a series of separate vapor condensing chambers maintained at progressively lower temperatures 35 and refluxing a regulated part of the condensate from condensing chambers of lower temperature to condensing chambers of higher temperature.

The present invention, in certain aspects, 40 relates to further improvements in the method described in said application, and the improved method of the present invention may also include fractionation of the vapors from a reflux tower on a pressure still by passing 45 them successively through a series of vapor condensing chambers maintained at progressively lower temperatures and refluxing a regulated part of the condensate from the condensing chambers of lower temperature to 50 condensing chambers of higher temperature.

According to the present invention, fresh charging stock introduced into the pressure still may be employed in both the refluxing operation and the fractionating operation 55 and the charging stock employed in each of these operations thereby preheated. By directly fractionating the vapors from the reflux tower on the pressure still, the heat employed in redistilling condensed pressure 60 distillate is saved, and even where the fractions directly separated are subjected to further fractionation, heat is conserved to the extent of the direct initial separation effected. By preheating the feed, the burden of raising 65 the charging stock to the temperature pre-

vailing in the pressure still is removed from the heating surfaces of the pressure still to an extent corresponding to the temperature to which the feed is preheated; and by employing the latent heat of the vapors escaping 70 from the reflux tower for preheating the feed employed in cooling and condensing the vapors undergoing fractionation, the heat usually lost in condensing the pressure distillate escaping as vapors from the reflux tower 75 is returned to the pressure still where it may be employed in the cracking operation.

In the combined operation of the invention these factors, among others, cooperate in increasing the efficiency of the cracking operation and the capacity of the pressure still by increasing the relative amount of heat actually employed in the conversion of high boiling point oils to lighter or more volatile oils. The practice of the process of the present invention enables heat losses due to the latent heat of vaporization of the pressure distillate, usually carried off in the cooling medium employed in condensing the vapors from the reflux tower on the pressure still, to be eliminated or minimized. The fresh feed is employed for cooling and fractionally condensing the vapors from the pressure still and at the same time the vapors from the still are employed in further fractionating the condensed fractions. The heat of condensation of the pressure distillate is thus used to advantage in preheating fresh charging stock and in fractionating the distillate. The amount of heat required for redistillation is 100 reduced and in some cases this operation is eliminated.

According to the present invention, fresh oil or reflux may be introduced into direct contact with the vapors in the refluxing operation at a series of successive points as the refluxing operation proceeds; and progressively lighter or lower boiling fractions may be introduced progressively into the vapors from the pressure still as they proceed 110 through the refluxing operation. Where separate fractions of different characteristics are introduced directly into the reflux tower on a pressure still in accordance with the invention, each separate fraction may thus be introduced at the point most advantageous for its treatment and for control of the refluxing operation, and where progressively lighter or lower boiling oils are progressively introduced at successively higher points in the reflux tower, as the vapors from the pressure still proceed therethrough, the temperature gradient through the refluxing tower may be controlled and regulated and an improved refluxing secured. Where the oil introduced 125 into the reflux tower contains constituents which are vaporized therein, the cooling effect of the fresh oil, or cool reflux, is supplemented by the vaporization of these constituents, in whole or in part.

Separate fractions for introduction into the reflux tower and for regulating and controlling the refluxing operation therein, may be withdrawn from the succeeding fractionating operation of the invention, or fresh charging stock which has been employed in cooling and condensing the vapors undergoing fractionation by indirect heat exchange may be employed for this purpose, or fractions of suitable character from other sources may be employed, or various fractions from such sources may be employed jointly.

The present invention also provides an improved method of operation which affords close control of both the refluxing operation and the fractionating operation. For regulating the reflux operation, a condensed fraction, corresponding to the desired distillate to be withdrawn from the refluxing operation as a vapor, may be introduced directly into the upper part of the reflux tower. Additional feed, for introduction into the refluxing operation, may be introduced in admixture with this fraction or may be separately introduced at a lower point in the reflux tower. The fractionating operation may similarly be regulated and controlled, as described in the prior application hereinbefore mentioned, by passing the vapors from the reflux tower through a series of separate vapor condensing chambers maintained at progressively lower temperature and refluxing a regulated part of condensate from cooler chambers into direct contact with the vapors in hotter chambers.

By returning a condensed fraction corresponding to the fraction it is desired to separate, in either the refluxing operation or the fractionating operation, the character of the vapors escaping from each operation may be closely controlled, the returned material being vaporized, and cooling and condensing the vapors into which it is introduced by vaporization, tending to condense all constituents of a heavier character and thus limiting the boiling point of the escaping fraction. In the combined operation of the present invention, both the refluxing operation and the fractionating operation may be so regulated, and separate fractions collected in the fractionating operation, as well as the final product, may be closely controlled. Condensate from the fractionating operation may be employed for introduction into the refluxing operation, and where the heaviest fraction separated in the fractionating operation is so employed, the vapors escaping from the refluxing operation will not contain any substantial amount of heavier material.

In carrying out the method of the present invention, condensates separated in the fractionating operation may be refluxed or otherwise returned to the still, either directly or through the refluxing operation, or they may

be separately disposed of. The heavier condensates separated in the fractionating operation may be introduced into direct contact with the vapors in the refluxing operation for controlling and regulating the character of the distillate escaping from the refluxing operation; or the lighter condensates may be subjected to separate cracking treatment or may be put to other use.

The reflux from the refluxing operation includes, in addition to the condensed heavier vapors from the pressure still, separated in the refluxing operation, the unvaporized part of any fresh charging stock, or of any refluxed condensate from the fractionating operation, introduced into direct contact with the vapors subjected to the reflux operation; and this reflux is returned to the pressure still for further treatment therein for the production of additional amounts of the desired lighter hydrocarbons.

The present invention includes an improved operation in which the vapors from a pressure still are subjected to a refluxing operation in direct contact with fresh charging stock to the still and then to a fractionating or refluxing operation in indirect heat exchange with fresh charging stock, and in which the fresh charging stock introduced into the first refluxing operation may have been, in part or wholly, employed in indirect heat exchange with the vapors in the fractionating operation or second refluxing operation.

The present invention also includes an improved operation in which the vapors from a pressure still are subjected to a refluxing operation and then to a fractionating operation in which the vapors from the refluxing operation are passed successively through a series of separate vapor condensing chambers maintained at progressively lower temperatures and in which a regulated part of condensate from chambers of lower temperatures is refluxed to chambers of higher temperature.

The present invention also includes an improved operation in which the vapors from a pressure still are successively subjected to a refluxing operation and a fractionating operation in which the character of the vapors escaping from the refluxing operation to the fractionating operation is controlled by the return of condensate from the fractionating operation into direct contact with the vapors in the refluxing operation.

The present invention also includes an improved refluxing operation in which a plurality of separate fractions are separately introduced into direct contact with the vapors subjected to the refluxing operation, and an improved operation in which the vapors from a pressure still are progressively subjected to the refluxing action of a series of progressively lighter fractions successively introduced

into direct contact with the vapors from the pressure still.

In carrying out the process of the present invention for the production of gasoline, the refluxing operation may be regulated so that all material suitable for treatment in the pressure still may be refluxed to the pressure still for further treatment therein and the fractionating operation may be regulated so that such heavier fractions as may be desired, or such as are not suitable or as are not desired for further treatment in the pressure still, for example, kerosene or the lighter constituents of the pressure distillate undesirable in commercial gasoline, may be separated in the fractionating operation. The gasoline product may be collected as one of the constituents separated in the fractionating operation, or the fractionating operation may be regulated to permit the gasoline fraction to escape and to be separately condensed and collected.

The oil employed for cooling and condensing the vapors by indirect heat exchange in the fractionating operation may be introduced, in whole or in part, directly into the pressure still, or may, in whole or in part, be introduced into direct contact with the vapors undergoing fractionation, in one or more of the stages of the fractionating operation, or may be directly introduced into the refluxing operation in whole or in part. Where the fresh oil employed for cooling and condensing the vapors undergoing fractionation contains lighter constituents, suitable as components of the gasoline product, or of one or more of the desired products separated in the fractionating operation, it may be introduced directly into the refluxing operation after cooling and condensing the vapors undergoing fractionation, and the oil partially distilled therein, the vaporized constituents escaping to the fractionating operation with the vapors from the refluxing operation.

Crude oil, or other fractions or distillates including constituents suitable as components of commercial gasoline as well as heavier constituents, may be treated in this manner to produce a merchantable gasoline product in a single combined operation, the lighter constituents being vaporized in the refluxing operation, after being preheated by indirect heat exchange in the fractionating operation, and subjected to fractionation with the vapors from the refluxing operation, and the heavier constituents introduced into the pressure still for cracking, the lighter constituents from the pressure distillation being subjected to the refluxing operation and then escaping to the fractionating operation with the constituents vaporized from the fresh oil in the refluxing operation. A gasoline product may thus be produced directly from crude oil, or from distillates including constituents boiling over a wide range, without separate fractionation of the material subjected to the cracking operation and without separate redistillation of the cracked products from the pressure distillation. Other products, as may be desired, may be separated or produced and collected at the same time.

Where the process of the present invention is carried out in conjunction with a pressure distillation in a circulatory pressure still, reflux from either the refluxing operation or the fractionating operation, and fresh charging stock employed for cooling and condensing the vapors undergoing fractionation by indirect heat exchange, may, with advantage, be introduced into the circulating stream of oil. Where the fresh charging stock or the refluxed oil includes lighter constituents, heavier than the components of any of the products desired which, however, are vaporized readily under the conditions prevailing in the pressure still and which are more or less refractory to cracking, the oil, or such part of it as may contain such lighter constituents, may be introduced into the circulating stream of oil entering the cracking zone and the lighter constituents subjected to the cracking conditions of temperature and pressure in the cracking zone before any substantial vaporization is effected, or during such vaporization. Where the process of the invention is carried out in conjunction with a pressure distillation in a single pass cracking still, charging stock which has not yet been subjected to the pressure distillation may be introduced into the heating element at one point and the various refluxed oils and separated fractions returned to the cracking treatment may be introduced at other points, as may be appropriate to their composition and characteristics.

The improved apparatus of the invention includes a pressure still with a reflux tower thereon and means, such as a fractional condenser or fractionating tower, for fractionating the vapors from the reflux tower and for preheating the feed by bringing it into indirect heat interchanging relation with the vapors undergoing fractionation. The improved apparatus is intended and adapted for carrying out the improved process of the invention, and includes various features of novelty in its construction and its arrangements of parts which will be hereinafter more fully pointed out and described.

In the accompanying drawings I have shown certain forms of apparatus embodying and illustrating the invention and in which the process of the invention can be practiced, and the invention will be further described in connection therewith. It is to be understood, however, that these specific illustrations and description are for the purpose of exemplification, and that the scope of the invention is defined in the following claims, in which I have endeavored to distinguish it

from the prior art, without, however, relinquishing or abandoning any portion or feature thereof.

In the accompanying drawings:

5 Fig. 1 is a fragmentary, axial, longitudinal, sectional view of a fractionating tower adapted for use in conjunction with the pressure still and reflux tower for carrying out the fractionating operation of the process of
10 the invention,

Fig. 2 represents in elevation and partly in section a fractionating tower of the type shown in Fig. 1 arranged in conjunction with a pressure still having a reflux tower thereon, 15 and

Fig. 3 represents a modified arrangement of the apparatus illustrated in Fig. 2.

Each part is identified with the same reference character wherever it occurs throughout the drawings.

The fractionating tower shown in the drawings is of the general type described and illustrated in Patent 1,489,420 granted to the Sinclair Refining Company April 8, 1924 on 25 my application.

Referring to the drawings, the fractionating tower comprises a vertical shell 4 closed by end plates 5, each of which is provided with a hand hole fitting 6. The hand holes 30 are normally closed by plates 7 and 8. Slightly separated from the end plate 5 at each end of the tower are header sheets 9 and 10, said sheets forming with the adjacent end plates, inlet and outlet chambers 11 and 12, for the 35 cooling oil as will presently appear. The space between the header sheets is divided into a plurality of vapor condensing chambers 13, shown as four in number, although the number may be varied and is dependent 40 upon the number of separate fractions or cuts desired. Between adjacent condensing chambers are chambers 14 for the cooling oil, formed by header sheets 15 on opposite sides thereof. The header sheets are successively 45 connected by batteries of tubes 16 extending through the respective vapor condensing chambers whereby the cooling oil may flow the length of the tower through the successive sets of tubes and intermediate chambers. The 50 vapor chambers are provided with suitable baffle plates 17 fitting loosely about the cooling tubes to provide a circuitous circulation for the vapors therethrough in order that they may be more thoroughly brought in contact and in heat exchanging relation with the 55 cooling tubes.

The lowermost of the vapor condensing chambers is provided with an inlet port 18 for the entrance of the vapors and the uppermost condensing chamber with a vapor outlet 19. Connections 20 are provided to conduct the vapors, or such portion thereof as remains uncondensed, from each vapor chamber, except the topmost, to the vapor condensing chamber next above, arranged to connect the

adjacent condensing chambers about the intermediate chambers for the cooling oil, the point of connection to the upper vapor condensing chamber being sufficiently above the header sheets forming the bottom of that chamber to allow for the collection of liquid condensate therein. In order to supplement control of the fractionation effected in the separate vapor condensing chambers, connections are provided for controlling and distributing the flow of cooling oil passing through the tubes on its way to the pressure still through the respective batteries of tubes in the separate vapor condensing chambers. For this purpose, each of the intermediate cooling fluid chambers 14 is provided with an outlet 31, these outlets being connected to a common bypass pipe 32, the various connections being provided with valves at appropriate points as illustrated.

Each condensing chamber near its bottom and below the level of the vapor connection thereto has a drawoff pipe 23 which is provided at 36 with a gauge glass to indicate the level of the condensate in the chamber and a valve 37 for shutting off the drawoff and controlling the passage of condensate therethrough. A pipe 38 connected to the gauge glass receptacle extends to a cooler or storage tank. A branch connection 39 leads from the drawoff 23 of each condensing chamber, except the lowermost to the top of the next lower condensing chamber at 40, a trap being formed in said pipe at 41 and a valve located herein at 42. A regulated part of the condensate from each condensing chamber may be refluxed through this connection to the next lower and hotter condensing chamber where it is revaporized and returned for further treatment, the amount of reflux so introduced into the next lower and hotter chamber being controlled by valve 42. A stream of condensate entering the top of each condensing chamber from pipe 40 spreads over the topmost baffle therein, and, the holes in baffle through which the cooling tubes extend being somewhat larger than the latter, forms films on the tubes until vaporized being thus effectively subjected to the temperature of the tubes. Refluxed condensate is thus in effect redistilled and refractionated securing a more definite cut while at the same time effecting a regulated condensation of the vapors in the chamber into which it is introduced.

The pressure still shown in the drawings is of the general type described and illustrated in Patent 1,285,200 granted to the Sinclair Refining Company November 19, 1918, on the application of Edward W. Isom. The process of the invention is of special value and application in connection with a pressure still of this type, but it will be understood that the invention is of more general application.

The pressure still illustrated in Figs. 2 and

3 is made up of the bulk supply tank 43 located away from the heating furnace 44, the vertical heating tubes 45 arranged in the heating flue 46 of the furnace, and circulating pipes 47, 48 and 49 connecting the lower and upper ends of the vertical tubes with the bulk supply tank and a circulating pump 50 for circulating the oil from the bulk supply tank through the vertical tubes and back to the bulk supply tank. Arranged above the bulk supply tank is a reflux tower 51 having a series of baffles therein and connected with the vapor dome of the bulk supply tank through the vapor line 52. A return reflux line 53 having a check valve therein to prevent flow into the reflux tower is provided for the return of reflux to the pressure still. The vapors from the top of the reflux tower escape from the vapor line 54 to the fractionating tower 55. The vapors pass upwardly through the fractionating tower, undergoing fractional condensation therein, and any uncondensed vapors and gases escape from the top of the tower through connection 56. The vapors escaping through connection 56 may be conducted to a separate condenser, or, where they contain no valuable condensable material, may be conducted to a gas holder, or may be otherwise disposed of. A connection 57 is provided for supplying cooling oil to the bearings of the circulating pump 50. A continuous tar drawoff is shown at 58 and a pumping out line for discharging the still is shown at 59.

35 The fractionating tower and the reflux tower, and the various connections carrying hot oil or hot vapors may be suitably insulated to prevent heat loss and to promote the efficiency of the operation. The pressure may be regulated and reduced by means of a regulated valve 24 between the reflux tower and the pressure still and the reflux tower operated at a pressure lower than that prevailing in the still. The reflux tower may also be operated at substantially the pressure prevailing in the still and the pressure in the still and the reflux tower may be regulated and reduced by means of valve 25 between the fractionating tower and the reflux tower, and the fractionating tower operated at a pressure lower than that prevailing in the still and reflux tower. The pressure may also be regulated and reduced by means of a regulating valve 26 beyond the fractionating tower, or where a separate condenser is employed by the fractionating tower, the pressure may also be regulated and reduced by appropriate valves located beyond the condenser. The reflux tower and the fractionating tower, and the separate condenser if one is employed, may be operated at the same pressure or at different pressures, and at atmospheric pressure or at some intermediate pressure. The reflux tower and the fractionating tower may be operated at substantially still pressure or

at some lower pressure, and the fractionating tower may be operated at the same pressure as the reflux tower or at lower pressures. Intermediate pressures may be maintained in the reflux tower and in the fractionating tower and the pressure may be progressively reduced from still pressure to atmospheric pressure, or some intermediate pressure, as the vapors proceed from the still.

Where the reflux tower is operated at substantially the pressure prevailing in the pressure still, reflux may be returned to the still from the tower through connection 60 to the inlet side of the circulating pump (by opening valves 61 and 62), or through connections 65 and 66 to the eduction outlet between the pump and the heating tubes (by opening valves 62, 63 and 67); or where the reflux tower is operated at a reduced pressure, a pump 68 is provided for returning reflux to the pressure still; either through connection 60 (by opening valves 64, 69, 70 and 63 and closing valve 62,) or through connections 65 and 66 (by opening valve 67). Condensate from the fractionating tower may be introduced into the top of the reflux tower through connection 71, or directly introduced into the pressure still either through connection 60 (by opening valves 61, 63 and 70) or through connections 65 and 66 (by opening valves 67 and 70) by means of pump 72.

Fresh charging stock is circulated through the tubes 16 in the fractionating tower by means of pump 78. The hot vapors from the reflux tower enter the hottest and lowermost vapor condensing chamber through connection 54 and pass upwardly through the successive vapor condensing chambers maintained at progressively lower temperatures undergoing partial condensation in each condensing chamber. Any uncondensed vapors or gases escape from the uppermost and coolest condensing chamber through connection 56. The heaviest vapors are condensed in the lowermost and hottest chamber, the next heaviest vapors in the next chamber, and the progressively lighter vapors in the successive chambers, the condensate in each chamber being separately collected in the lower part of that chamber. The liquid condensate collecting in the lowermost chamber may be returned to the pressure still or to the reflux tower through connection 73 or may be withdrawn, in whole or in part, through valved connection 74; and condensate collecting in the other chambers of the series may be withdrawn through the valved connections 38. A regulated part of the condensate collecting in each of the chambers, except the last, may be refluxed into the next lower and hotter chamber through the connections 41, the amount of condensate so returned being controlled in each instance by the valves 42 in the communicating connections.

Fresh charging stock is also introduced into

- the reflux tower 51 through connection 75. This charging stock may be supplied by means of pump 76 through connection 77, or may be reflux from the fractionating operation supplied by pump 72 through connection 71, or may be preheated stock which has been circulated through the cooling tubes in the fractionating tower supplied through connections 71 and 79 by pump 78.
- 10 The charging stock circulated through the fractionating tower for cooling and condensing the vapors undergoing fractionation therein may be directly introduced, in whole or in part, into the pressure still, after indirect heat exchange with the vapors undergoing fractionation, through connections 79, 65 and 66, or may, in whole or in part, be introduced into the reflux tower through connections 79, 71 and 75; or all or a part of the preheated charging stock leaving the fractionating tower through the lower connection 25 may be introduced into one or more of the vapor condensing chambers 13 through valved inlet connections 80, for example, into one or more of the lower condensing chambers, for supplementing the cooling and condensation of the vapors in the fractionating tower. The fresh oil circulated through the fractionating tower in indirect heat exchange with the vapors therein may, for example, be introduced directly into the lowermost condensing chamber, and then introduced into the reflux tower or into the pressure still in admixture with the condensate from the lowermost condensing chamber. The preheated oil thus introduced may also be partially vaporized in the lowermost condensing chamber. Additional oil may also be introduced into the pressure still through connection 66 by means of pump 81.
- 15 The several pumps 76, 78 and 81 may draw from a common supply receptacle, or separate charging stocks may be introduced, in varying amount, into the refluxing operation, through the fractionating operation for cooling and condensing the vapors therein by indirect heat exchange, and directly into the pressure still, as is most appropriate to the character of each stock and to the proportionate quantity of the various stocks to be treated.
- 20 Fresh charging stock may be introduced into the refluxing operation independently of that passed through the fractionating operation for cooling and condensing the vapors by indirect heat exchange, and the refluxing and fractionating operations may be controlled, within limits, by the respective amounts of fresh stock so circulated through the fractionating tower and so introduced into the reflux tower. Where the cooling effected by that part of the feed circulated through the cooling tubes in the fractionating tower is insufficient, additional cooling oil, in addition to that used as charging stock,
- 25 may be circulated therethrough and bypassed back to the supply receptacle, or a part of the fresh oil circulated through the cooling tubes may be directly introduced into one or more of the condensing chambers to supplement, by direct contact or by partial vaporization, the cooling effected by indirect heat exchange. Where the amount of feed introduced into the reflux tower and circulated through the fractionating tower to maintain the appropriate temperature control of these two operations is insufficient to maintain the charge in the pressure still, additional and supplemental feed is introduced directly into the pressure still.
- 30 Where complete condensation is effected in the fractionating tower 55, or where for any other reason the maximum cooling effect is desired in the fractionating tower 55, all of the charging stock to the pressure still may be circulated through the cooling tubes in the fractionating tower and then introduced into the pressure still, a sufficient amount of the fresh preheated stock leaving the fractionating tower through connection 25 being introduced directly into the refluxing tower through connection 75 to effect the required refluxing operation therein, the remainder being introduced directly into the pressure still. Reflux condensate from the fractionating tower may also be introduced, in whole or in part, into the reflux tower in admixture with that part of the preheated stock introduced therein, or may be returned to the pressure still directly.
- 35 Where separate stocks are being treated, and part of the fresh stock treated contains constituents suitable as components of one or more of the finished products, the stock containing such lighter constituents is introduced directly into the reflux tower and the lighter constituents are vaporized therein, the resulting vapors and uncondensed vapors from the pressure still passing to the fractionating tower where they are separated and collected in the appropriate fractions. If the stock containing such lighter components is insufficient in amount to effect the desired refluxing operation, it may be introduced in admixture with other fresh charging stock into the reflux tower. Where a separate charging stock is employed for cooling the fractionating tower by indirect heat exchange, a part of this separate charging stock may be admixed with the feed to the reflux tower. Stock containing such lighter constituents may also be introduced through the fractionating tower, either alone or in admixture with other stocks, before being introduced into the reflux tower.
- 40 Where a part of the stocks to be treated include stocks containing lighter constituents which vaporize rapidly under the conditions maintained in the pressure still but which, however, are not desirable as components of

any products of the operation, such fresh stocks are introduced directly into the circulating oil in the pressure still where they are circulated through the heating elements before being permitted to escape from the still as vapors and are thus subjected to the cracking conditions of temperature and pressure maintained in the heating elements. Where the stock of this character is of relatively small amount, it may be introduced directly into the circulating line of the still, or if in larger amount, it may first be circulated through the cooling tubes in the fractionating tower and then introduced into the circulating line of the still.

Reflux condensate from the fractionating tower, or fresh feed of a corresponding character, may be directly introduced into the refluxing operation, either alone, or with other feed, for regulating and controlling the refluxing operation and limiting the boiling range of the fraction escaping from the refluxing operation to the fractionating operation. Heavier condensates collected in the fractionating tower may also be introduced into the circulating line of the pressure still to insure their subjection to the cracking conditions of temperature and pressure maintained in the heating element, or they may be withdrawn and separately treated.

Where a large part of the stock to be treated includes constituents suitable as components of any of the desired products the fresh stock may be circulated through the fractionating tower in indirect heat interchanging relation with the vapors therein and is then introduced directly into the reflux tower where the lighter constituents suitable as components of any of the products of the operation are vaporized and escape with the vapors from the refluxing operation to the fractionating operation. Additional stock may be circulated through the cooling tubes in the fractionating tower and by-passed back to the supply to increase the cooling effect therein, and additional feed may be introduced into the refluxing tower in admixture with the preheated stock leaving the fractionating tower through connection 25 to increase the refluxing effect of the preheated oil introduced into the reflux tower from the fractionating tower.

If any substantial part of the oil circulated through the fractionating tower for cooling and condensing the vapors from the reflux tower on the pressure still is vaporized within the cooling tubes, it may retard the circulation or otherwise decrease the effective heat exchange in the tower. Accordingly, where the stock brought into indirect heat exchange with the vapors in the fractionating tower contains lighter constituents, the circulation is regulated so that no substantial part of such constituents are vaporized at the highest temperature to which the fresh oil is pre-

heated in the tower. Vaporization may also be inhibited by increasing the pressure upon the fresh charging stock. The pressure required to force the oil through the cooling tubes into the still, a pressure somewhat in excess of the still pressure, may be supplemented and increased by a regulating valve in the outlet from the cooling tubes.

Where it is desired to take off an increased amount of distillate from the pressure still as vapors from the top of the reflux tower, a part of the fresh charging stock employed in cooling and condensing the vapors undergoing fractionation by indirect heat exchange is introduced, together with any additional feed required for maintaining the still charge, directly into the pressure still. The refluxing effected in the reflux tower may be increased, and controlled, by return to the refluxing operation of a regulated part of one or more of the heavier condensates separated in the fractionating operation.

In one way of carrying out the process of the invention, fresh oil or reflux condensate is introduced into direct contact with the vapors undergoing refluxing, and for this purpose, a series of inlets for the direct introduction of oil may be provided as shown in Fig. 3. In the operation of the apparatus there illustrated and in this way of carrying out the process of the invention, the lightest fraction introduced into the reflux tower is introduced through the top connection 82, the next lighter fraction through the next lower connection 83 and the next lighter fraction through the bottom connection 84. Three separate inlets are illustrated, but two inlets or a greater number of inlets could be employed.

Where the feed employed for cooling and condensing the vapors undergoing fractionation by indirect heat exchange is of a light character, or contains a substantial amount of lighter constituents, it may be introduced into the reflux tower through the connections 79, 71 and 82, and reflux from the fractionating tower introduced through connections 73, 85 and 83. Any heavier feed may be introduced by means of pump 76 through connections 77 and 84. Where one of the stocks to be treated contains a substantial amount of lighter constituents but is insufficient in amount to effect the necessary cooling in the fractionating tower, it may be introduced into the reflux tower through connections 77 and 82, and reflux from the fractionating tower may be introduced through connections 73, 85 and 83. Heavier fresh stock employed in cooling and condensing the vapors undergoing fractionation by indirect heat exchange may be circulated through the fractionating tower and then introduced, in whole or in part, through connections 79, 71 and 84.

In carrying out the process of the invention for the production of gasoline, the heavier

vapors are condensed in the reflux tower 51 by heat exchange with the fresh feed, which may be of a gas oil character, introduced into the upper end of the tower and are returned 5 to the pressure still for further treatment together with the unvaporized part of the feed introduced into the reflux tower. The vapors escaping from the reflux tower through connection 54 comprise the gasoline component, 10 kerosene character fractions, and some heavier vapors. The gasoline fraction, together with the heavier fractions, may be separately condensed in the fractionating tower 55, or the fractionating tower 55 may be operated so as 15 to separate the heavier components from the gasoline fraction and the gasoline fraction may be withdrawn from the fractionating tower through connection 56 as a vapor and conducted to a separate condenser.

20 Where the gasoline fraction is condensed in the fractionating tower, the gasoline may be condensed in the upper two chambers, the kerosene condensed in the next to the bottom chamber, and the heavier fractions condensed 25 in the lowest chamber. The kerosene character fraction may be withdrawn for separate treatment or to be put to other use, and the heavier condensate collected in the bottom chamber may be returned to the cracking operation, either directly to the pressure still 30 or through the reflux tower. Where the gasoline fraction is separately condensed, the heavier fractions may be separated into various cuts in the chambers of the fractionating tower, for example, kerosene character fractions may be collected in the top two or the top three chambers and a heavier fraction or 35 fractions collected in the lower chamber or chambers. The fractions condensed in the 40 chambers of the tower may be marketed as such, or after further refining treatment; or the different fractions may be blended with each other in a variety of ways according to 45 the specific composition desired.

45 Where the desired gasoline fraction is condensed in one or more of the upper condensing chambers in the fractionating tower, very close regulation of the gasoline fraction can be secured by returning to the lower condensing 50 chambers a regulated part of the gasoline condensate from the upper chambers at a point adjacent the outlet through which the vapors escape to the next condensing chamber. The gasoline character fraction so 55 returned is vaporized and in vaporizing promotes the condensation and fractionation in the chamber into which it is introduced, and substantially reduces the amount, if any, of vapors escaping to the final condensing chamber of a character substantially heavier than 60 the refluxed gasoline fraction. The pressure still and fractionating tower can be operated in this way for the direct production of a marketable gasoline fraction without redistillation of the pressure distillate. Where a 65

separate condenser for the final gasoline fraction is employed, a similar effect can be secured by returning to one or more of the upper condensing chambers in the fractionating tower a part of the final gasoline fraction 70 collected in the separate condenser.

The process of the present invention may be employed for the direct treatment of a crude oil, or of a distillate containing gasoline character constituents, for the production of gasoline in a single combined operation of high efficiency. The crude gasoline containing material may be circulated through the fractionating tower in indirect heat exchanging relation with the vapors 75 therein at a rate and under pressure sufficient to prevent substantial vaporization and thereby preheated, the vapors from the still at the same time being fractionally condensed 80 the heat of the vapors being employed for preheating the fresh charging stock and for effecting a further fractionation of the condensates, thereby eliminating the step of redistillation of the crude pressure distillate, 85 while at the same time returning the heat in 90 the vapors from the pressure still to the pressure still where it can be employed in the useful part of the cracking process. The preheated crude material may then be introduced directly into the reflux tower and the 95 gasoline character constituents separated by vaporization, the introduced oil promoting the refluxing operation both by its sensible heat and by the heat of vaporization of the lighter constituents, and the unvaporized 100 part of the fresh charging stock introduce into the reflux tower together with the reflux from the reflux tower introduced into the pressure still for cracking treatment. For regulating the operation, part of the fresh oil circulated 105 through the fractionating tower in indirect heat exchanging relation with the vapors undergoing fractionation may be introduced directly into the pressure still, or additional 110 fresh oil may be introduced into the reflux tower in admixture with the preheated fresh oil from the fractionating tower.

The process of the present invention may be combined with a pressure distillation where tar is drawn off from the pressure still 115 during the progress of the operation, and particularly where during the latter part of the pressure distillation tar is withdrawn in relatively large amount, and where fresh oil is introduced, to maintain the concentration of 120 tarry constituents below an objectionable point during the progress of the operation. In such a combined operation, fresh charging stock, in an amount corresponding to the condensed fractions withdrawn from the operation and any vapors withdrawn from the fractionating tower, may be introduced into the pressure still through the fractionating tower in indirect heat exchange with the vapors 125 therein and then directly into the re- 130

flux tower; and any additional feed required for maintaining the still charge approximately constant as far as withdrawn may be introduced into the still directly, or in part directly and in part into the reflux tower, or in part through the fractionating tower into the still or into the reflux tower.

It will be apparent that in one aspect this invention provides an improved operation, which, substituted for the customary final condensation of the vapors discharged from the reflux tower on a pressure still, effects a separation of the vapors into the desired fractions directly as they come from the pressure still without redistillation, and in which the heat usually lost in condensing and redistilling the pressure distillate is conserved by employing fresh charging stock on its way to the pressure still for cooling and condensing the vapors undergoing fractionation and by employing the hot vapors undergoing fractional condensation for preheating the fresh charging stock so employed before introduction into the still.

It will also be seen that the present invention provides an improved process in which the heat of the vapors from the pressure still may be employed for effecting an initial separation of fresh charging stock subjected to the process by distilling from the fresh charging stock the lighter constituents suitable as components of the finished product or products before such constituents are subjected to the cracking operation proper.

One of the important advantages of the invention is the elimination or reduction in amount of redistillation of crude pressure distillate and the heat economy effected by employing the heat of the vapors from the pressure still for preheating the feed and for effecting an improved fractionation of the crude pressure distillate. Another important advantage of the invention is its flexibility and its adaptability of the treatment of a wide range of materials and its ability to make use, to advantage, of several charging stocks of different characteristics.

I claim:

1. The improvement in the operation of pressure stills for cracking hydrocarbon oils and distillates, which comprises subjecting the vapors from the still to a refluxing operation in a zone separate from the vaporizing zone in direct contact with fresh charging stock to the still, returning the reflux and unvaporized charging stock introduced into the refluxing operation to that portion of the still stock which is to be immediately subjected to high temperature, subjecting the vapors from the refluxing operation to a fractional condensation in indirect heat exchanging relation with fresh charging stock and introducing the fresh charging stock so preheated directly to the pressure still.

2. The improvement in the operation of

pressure stills for cracking hydrocarbon oils and distillates, which comprises subjecting the vapors from the still to a refluxing operation in a zone separate from the vaporizing zone in direct contact with fresh charging stock to the still, returning the reflux and unvaporized charging stock introduced into the refluxing operation to that portion of the still stock which is to be immediately subjected to high temperature, subjecting the vapors from the refluxing operation to a fractional condensation in indirect heat exchanging relation with fresh charging stock, introducing a part of the fresh charging stock employed in the fractional condensation directly into the refluxing operation, and introducing another part of the charging stock employed in the fractional condensation directly to the pressure still.

3. The improvement in the operation of pressure stills for cracking hydrocarbon oils and distillates, which comprises subjecting the vapors from the still to a refluxing operation in a zone separate from the vaporizing zone and then to a fractional condensation in indirect heat exchanging relation with fresh charging stock to the still, regulating the refluxing operation by introducing near the point of discharge of the vapors from the reflux operation part of the heavier condensate condensed in the fractional condensation, and introducing preheated stock from the fractional condensation directly to the pressure still.

4. The improvement in the operation of pressure stills for cracking hydrocarbon oils and distillates, which comprises subjecting the vapors from the still to a refluxing operation in a zone separate from the vaporizing zone in direct contact with fresh charging stock to the still, returning the reflux and unvaporized charging stock introduced into the refluxing operation to that portion of the still stock which is to be immediately subjected to high temperature, passing the vapors from the refluxing operation successively through a series of separate vapor condensing chambers maintained at progressively lower temperature, passing fresh charging stock to the still in indirect heat interchanging relation with the vapors in the condensing chambers, refluxing a part of the condensate from chambers of lower temperature to chambers of higher temperature, and introducing preheated charging stock from the condensing chambers directly to the pressure still.

5. The improvement in the operation of pressure stills for cracking hydrocarbon oils and distillates, which comprises subjecting the vapors from a pressure still to a refluxing operation in a zone separate from the vaporizing zone and returning the reflux to that portion of the still stock which is to be immediately subjected to high temperature, pass-

ing the vapors from the refluxing operation successively through a series of separate vapor condensing chambers maintained at progressively lower temperature, passing 5 fresh charging stock to the still in indirect heat interchanging relation with the vapors in the condensing chambers, refluxing a part of the condensate from chambers of lower temperature to chambers of higher temperature, and introducing preheated charging 10 stock from the condensing chambers directly to the still.

6. The improvement in the operation of 15 pressure stills for cracking hydrocarbon oils and distillates, which comprises subjecting the vapors from the still to a refluxing operation in a zone separate from the vaporizing zone in direct contact with fresh charging stock to the still, returning the reflux and un- 20 vaporized charging stock introduced into the refluxing operation to the still, subjecting the vapors from the refluxing operation to a fractional condensation in indirect heat ex- 25 changing relation with fresh charging stock to the still, regulating the refluxing operation by introducing near the point of discharge of the vapors from the refluxing operation a regulated part of the heavier condensate in the fractional condensation, and introducing 30 preheated charging stock from the fractional condensation directly to the pressure still.

7. The improvement in the operation of 35 pressure stills for cracking hydrocarbon oils and distillates, which comprises subjecting the vapors from the still to a refluxing operation in a zone separate from the vaporizing zone, subjecting the vapors from the refluxing operation to a fractional condensation in indirect heat exchanging relation with 40 fresh charging stock to the still, whereby the vapors are condensed and the fresh charging stock is preheated, further fractionating part of the fractional condensates so produced by vaporization in direct contact with 45 fresh hot vapors from the reflux tower, and introducing preheated charging stock from the fractional condensation directly to the pressure still.

8. In combination, a pressure still, a reflux 50 tower, and a fractional condenser, connec- 55 tions for conducting vapors from the still to the reflux tower and for returning reflux to the still, connections for conducting vapors from the reflux tower to the fractional condenser, means for bringing fresh charging 60 stock to the still in heat interchanging relation with the vapors in the fractional condenser and connections for introducing charging stock from said last named means direct- 65 ly into the pressure still.

9. In combination, a pressure still, a reflux 70 tower separate from the still and a fraction- 75 ating tower, connections for conducting vapors from the still to the reflux tower and separate connections for returning reflux to

the still, connections for conducting vapors from the reflux tower to the fractionating tower, means for passing fresh charging stock to the still in direct contact with the vapors in the reflux tower, means in the fractionating tower for passing fresh charging stock to the still in indirect heat interchanging relation with the vapors therein, and connec- 75 tions for introducing fresh charging stock from said means into the pressure still. 75

10. In combination, a pressure still, a reflux tower separate from the still and a fractional condenser, means for introducing fresh charging stock to the pressure still into direct contact with vapors in the reflux tower, connec- 80 tions for conducting vapors from the still to the reflux tower and for returning reflux to the still, connections for conducting vapors from the reflux tower to the fractional condenser, means for bringing fresh charging stock to the still in heat interchanging relation with the vapors in the fractional condenser, connections for introducing charging stock from said last named means into the pressure still, and means for withdraw- 85 ing from the fractional condenser at least two fractions. 90

11. In combination, a pressure still, a reflux tower and a fractional condenser, connec- 95 tions for conducting vapors from the still to the reflux tower and for returning reflux to the still, connections for conducting vapors from the reflux tower to the fractional condenser, means for bringing fresh charging stock to the still in indirect heat exchanging 100 relation with the vapors in the fractional condenser and connections for conducting fresh charging stock from said last named means to the still, means for introducing heavier condensate from the fractional condenser into direct contact with the vapors in the reflux tower near the upper end there- 105 of, and means for introducing relatively heavier stock into direct contact with the vapors in the reflux tower at an intermediate point. 110

12. In combination, a pressure still, a reflux tower separate from the still and a fractional condenser comprising a series of condensing chambers adapted to be maintained 115 at progressively lower temperatures, connec- 120 tions for conducting vapors from the still to the reflux tower and for returning reflux therefrom to the still, connections for conducting vapors from the reflux tower to the fractional condenser, means for bringing fresh charging stock to the still in indirect heat exchanging relation with the vapors in the fractional condenser, connections for conducting fresh charging stock from said 125 last named means to the still and means for refluxing part of the condensate formed in the fractional condenser from chambers of lower temperature to chambers of higher temperature. 130

13. In combination, a pressure still, a reflux tower separate from the still and a fractional condenser comprising a series of condensing chambers adapted to be maintained at progressively lower temperatures, connections for conducting vapors from the still to the reflux tower, means for introducing fresh charging stock into direct contact with the vapors in the reflux tower and for returning reflux and said charging stock therefrom to the still, connections for conducting vapors from the reflux tower to the fractional condenser, means for bringing fresh charging stock to the still in indirect heat exchanging relation with the vapors in the fractional condenser, connections for conducting fresh charging stock from said last named means to the still through the reflux tower and means for refluxing part of the condensate formed in the fractional condenser from ¹⁵ chambers of lower temperature to chambers of higher temperature.
- 5 at progressively lower temperatures, connections for conducting vapors from the still to the reflux tower, means for introducing fresh charging stock into direct contact with the vapors in the reflux tower and for returning reflux and said charging stock therefrom to the still, connections for conducting vapors from the reflux tower to the fractional condenser, means for bringing fresh charging stock to the still in indirect heat exchanging relation with the vapors in the fractional condenser, connections for conducting fresh charging stock from said last named means to the still through the reflux tower and means for refluxing part of the condensate formed in the fractional condenser from ²⁰ chambers of lower temperature to chambers of higher temperature.
- 10 turning reflux and said charging stock therefrom to the still, connections for conducting vapors from the reflux tower to the fractional condenser, means for bringing fresh charging stock to the still in indirect heat exchanging relation with the vapors in the fractional condenser, connections for conducting fresh charging stock from said last named means to the still through the reflux tower and means for refluxing part of the condensate formed in the fractional condenser from ²⁵ chambers of lower temperature to chambers of higher temperature.

In testimony whereof I affix my signature.

JOHN E. BELL.
